G. W. RENZ

TYPEWRITING MACHINE

Filed June 16, 1923

UNITED STATES PATENT OFFICE.

GEORGE W. RENZ, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed June 16, 1923. Serial No. 645,720.

To all whom it may concern:

Be it known that I, GEORGE W. RENZ, a citizen of the United States, residing in borough of Bronx, in the county of Bronx, city and State of New York, have invented certain new and useful Improvements in Type-writing Machines, of which the following is a specification.

This invention relates to typewriting machines equipped for typing successive forms printed in succession upon fan-fold webs, as set forth, for example, in the patent to Wernery and Smith, No. 1,132,055, dated March 16, 1915, or for use with loose super-posed plies of work-web.

In Patent No. 1,358,033, granted to J. A. B. Smith, November 9, 1920, there is disclosed one of these fan-fold typewriting machines with equipment for using therein either one of two webs, the leading end of each web being attached to a platform or frame, and either of said frames being attachable to the typewriter carriage, while the other frame with its attached web rests upon the desk of the typewriter. In the foregoing machine, when it is desired to cease typing on one web and begin typing on the other, it is necessary to detach the frame that is in use, together with its web, and place the same upon the desk or in a receptacle, and then pick up the other frame with its attached web and secure it to the carriage of the typewriting machine.

One of the objects of the present invention is to provide a machine in which the change may be made from one fan-fold web or set of plies to the other fan-fold web or set of plies with greater celerity and convenience, and an object is to avoid the awkwardness which is involved in detaching the frames from the machine and depositing them upon the desk and then re-attaching them.

According to the present improvements, both fan-fold webs or both sets of superposed plies may be led part way into the machine, each web or set of plies forming a separate unit or pack, and both units or packs may be attached separately to the carbon-carrier which is usually employed in these machines for the purpose of facilitating the relative shifting between the plies of work-web and the sheets of carbon. On the carbon-carrier there are mounted, ac-

cording to the present improvements, two 55 sets of carbon-carrying blades, one set for one of the web units or packs and the other set for the other of the web-units. The leading ends of both units pass through these carbon-carrying devices; and one of the 60 units is carried forward and down around the platen to be typed upon. The other unit, however, is temporarily clipped to the carbon-carrier, so that said other unit merely moves forwardly and backwardly 65 in idleness as the carbon-carrier moves. In other words, the carbon-carrier must have its forward and backward movements that ordinarily accompany the line-feeding rotation of the platen and the relative shifting 70 movements of the carbons and work-web units; but during these forward and backward movements of the carbon-carrier for the typing of one of the work sheet units, the other work-web unit is drawn forwardly and 75 backwardly in idleness, being temporarily clipped to the carbon-carrier, and only one work-web unit at a time being fed around the platen to be typed upon.

Accordingly, when the typing of one form 80 upon one of the web units or packs is completed, and the carbons for said web are shifted, and the typed form is torn off, said web-unit may be withdrawn from the platen and clipped temporarily to the carbon-carrier, while the other web-unit may be unclipped from the carbon-carrier and pulled forwardly and passed down around the platen and up in front thereof for typing thereon; and, when the typing of a form is 85 completed, the carbons may be shifted back and the typed form may be torn off, and then the web unit or pack in question may be withdrawn from the platen and again clipped temporarily to the carbon-carrier. 90 Then the first web unit or pack may be released from its temporary clip and drawn forward and passed around the platen to type another of the forms thereon, and so on, the webs being used in alternation. Of 100 course, each web may be kept in use as long as it is necessary in order to type a succession of forms thereon before withdrawing it from the platen and advancing the other web into typing position.

Thus it will be seen that the two sets of carbon-carrying blades may be fixed or secured upon the single carbon-carrier which

reciprocates forwardly and backwardly upon tracks that are connected to the usual type-writer carriage to travel from left to right therewith; and shifting may be made from one web to the other with much greater convenience and celerity than heretofore, so that it becomes unnecessary to sort out the various memoranda which are to be typed upon the different web units or packs, in advance of typing any of them; inasmuch as each memorandum may be typed upon its appropriate web, and the next memorandum can be typed either upon the same web or upon the other web-unit, as occasion may require, so that sorting is rendered unnecessary and the work is speeded.

Other features and advantages will hereinafter appear.

In the accompanying drawings,

20 Figure 1 is a longitudinal sectional view of the machine with the device attached, and shows one of the work units or packs inserted around the platen in a position to be typed upon, and the other clipped to its portion of the carbon-carrier.

25 Figure 2 is a partial plan view of the carbon-carrier, showing the method in which one of the work units or packs is held by its clip, the clip for the second work unit or pack being thrown off.

30 Figure 3 is a front elevation of the carbon-carrier, showing the position thereon of the clips which hold the work units or packs.

35 As usual, a platen 5 is mounted in a carriage 6, in the back of which is mounted a work-frame 7. Feed-rolls 8 and 9 cooperate with the platen in the usual manner in feeding work-sheets or packs of work-sheets around the platen. Mounted on the work-frame 7 is a carbon-carrier 10, composed of a base 11 to which are fastened rollers 12, which engage rails 13 of the work-frame 7. Mounted on the base 11 is a plate 14, which 40 carries a plurality of carbon-blades 15. Also mounted on the plate 14 are the posts 16, preferably one at each of the four corners of the plate. The tops of the posts 16 are preferably reduced in size, as at 17, thus forming shoulders 18 which support a second plate 19 which is provided with openings to receive the reduced tops 17 and which also has mounted thereon a plurality of carbon-blades 20. Mounted near the front of the plates 14 and 19 are paper-clamps 21 and 22, provided with finger-pieces 23 and 24. The plate 14 has projecting from its lower surface a plurality of pins 25 which may pass through corresponding openings in the base 11, and which are furnished with slots 26 into which may be swung keys 27, preferably formed in the shape of pivoted levers which are mounted upon the under side of the base 11, as shown in Figures 1 and 2. The keys 27,

operating in conjunction with the pins 25, serve to lock the structure formed by the plates 14 and 19 and the posts 16 to the base 11 of the carbon-carrier.

To facilitate the backward movement of the carbon-carrier when withdrawing the carbons from a typed section of the work-sheet unit or pack, there is mounted on the lower plate 14 the hand-lever 28, which extends toward the front of the machine 70 where it is accessible to the operator. Mounted on the rear of the work-frame 7 are the transverse shafts 29 and 30, provided with paper-guides 31 and 32.

75 In operation a work-sheet unit or pack 33, made up of a plurality of work-sheets 33^a, is threaded into the machine over the transverse shaft 29, between the carbon-blades 15, after which the leading edge is bent back, and brought to a position in front of the lower edge of the plate 14, where it is fastened by the paper-clamp 21. Another work-sheet unit or pack 34, made up of a plurality of work-sheets 34^a, is 80 threaded in a similar manner into the machine over the transverse shaft 30, between the carbon-blades 20, and the leading edge is bent back in a similar manner and brought to a point in front of the plate 19, where it is fastened in place by the paper-clamp 22.

85 Assuming that memoranda of two different sorts are to be typed on the forms printed upon the work-sheet units or packs, and that the first memorandum is of the sort intended for the forms printed on the work-sheet unit or pack 33, the leading edge of that pack is released from its paper-clamp 21 and brought forward in the usual manner, and inserted underneath and around the platen. Upon completing the typing of the first memorandum on the work-sheet unit or pack 33, it may be supposed that the operator finds the second memorandum to be one that is to be typed upon the form 90 printed on the work-sheets of the work-web unit or pack 34. Accordingly, the operator withdraws the work-sheet unit or pack 33 from the platen, bends the leading edge toward the rear of the machine in order to 95 get it out of the way, and clips it in position upon the plate 14 by means of the paper-clamp 21. The operator then releases the leading edge of the work-sheet unit or pack 34 from the paper-clamp 22, straightens it out, draws it forward, and inserts it 100 underneath and around the platen and brings it to the typing position.

105 The part played by the feed-roll mechanism of the machine in this insertion and withdrawal of work-sheet units or packs is, of course, the obvious one of releasing the rolls when the work-sheet units or packs are being inserted or withdrawn, and of placing them in engagement with the work- 110

sheet units or packs when the latter are being line-spaced during the typing operation.

It is also obvious that the carbon-sheets 5 for the two work-sheet units or packs 33 and 34 will be bent back together with their work-sheets when they are not being typed upon and when they are being held by either of the paper-clamps 21 or 22, as il- 10 lustrated in Figure 1.

Variations may be resorted to within the scope of the invention, and portions of the improvements may be used without others.

Having thus described my invention, I 15 claim:

1. In a typewriting machine having a platen, in combination with feed-roll mechanism to feed a plurality of superposed packs of work-sheets interleaved with carbons successively or alternately around said platen, a carbon-carrier provided with a plurality of carbon-holding means, each of which in turn is provided with a plurality of carbon-holding blades, said carbon-holding 20 means being mounted one above another and so positioned as to permit some of said work-sheets or packs of work-sheets to remain interleaved with their respective carbons and partially threaded into said machine while one work-sheet or pack of work-sheets is being fed through the machine to be typed upon.

2. In a typewriting machine having a platen, in combination with feed-roll mechanism to feed a plurality of work-sheets or packs of work-sheets interleaved with carbons successively or alternately around said platen, a carbon-carrier provided with a plurality of carbon-holding means, each of said 30 carbons comprising a base fitted with a plurality of carbon-holding blades, said carbon-holding means being superimposed over one another in positions to permit some of said work-sheets or packs of work-sheets to remain interleaved with their respective carbons and partially threaded into said machine while one work-sheet or pack of work-sheets is being fed through the machine to be typed upon.

3. In a typewriting machine having a platen, in combination with feed-roll mechanism to feed a plurality of work-sheets or packs of work-sheets interleaved with carbons successively or alternately around said platen, a carbon-carrier provided with a plurality of carbon-holding means, each of said carbon-holding means comprising a base fitted with a plurality of carbon-holding blades, said carbon-holding means being superimposed over one another in positions to permit some of said work-sheets or packs of work-sheets to remain interleaved with their respective carbons and partially threaded into said machine while one work- 60 sheet or pack of work-sheets is being fed

through the machine to be typed upon, each of said carbon-holding means being provided with sheet-holding means to retain said partially threaded work-sheets or packs of work-sheets in inoperative position while 70 said other work-sheet or pack of work-sheets is being fed through the machine to be typed upon.

4. In a typewriting machine having a platen, in combination with feed-roll mechanism to feed a plurality of work-sheets or packs of work-sheets interleaved with carbons successively or alternately around said platen, a carbon-carrier provided with a plurality of carbon-holding means, each of said carbon-holding means comprising a base fitted with a plurality of carbon-holding blades, said carbon-holding means being superimposed over one another in position to permit some of said work-sheets or packs of work-sheets to remain interleaved with their respective carbons and partially threaded into said machine while one work-sheet or pack of work-sheets is being fed through the machine to be typed upon, each 80 of said carbon-holding means being provided with sheet-holding means to retain said partially threaded work-sheets or packs of work-sheets in inoperative position while 85 said other work-sheet or pack of work-sheets is being fed through the machine to be typed upon, said sheet-holding means each comprising a pivoted clamping member mounted on said base in a position to fasten a work-sheet or pack of work-sheets between it and 90 said base.

5. In a typewriting machine having a platen, in combination with feed-roll mechanism to feed a plurality of work-sheets or packs of work-sheets interleaved with carbons successively or alternately around said platen, a carbon-carrier provided with a plurality of carbon-holding means, each of said carbon-holding means comprising a base fitted with a plurality of carbon-holding blades, said carbon-holding means being superimposed over one another in position to permit some of said work-sheets or packs of work-sheets to remain interleaved with their respective carbons and partially 100 threaded into said machine while one work-sheet or pack of work-sheets is being fed through the machine to be typed upon, each of said carbon-holding means being provided with sheet-holding means to retain 105 said partially threaded work-sheets or packs of work-sheets in inoperative position while said other work-sheet or pack of work-sheets is being fed through the machine to be typed upon, said sheet-holding means each comprising a pivoted clamping member fastened to said carbon-holding means, said 110 clamping member being provided with a finger-piece with which it may be operated, and an upturned edge to guide it over a 115 sheet or pack of work-sheets is being fed

work-sheet or pack of work-sheets and thereby clamp it to said base.

6. In a typewriting machine, in combination, a platen, feed-rolls to guide a plurality of work-sheets or packs of work-sheets successively or alternately underneath and around said platen, and a carbon-carrier to which are secured a plurality of carbon-sheets in superposed groups, each group 10 containing a sufficient number of carbon-sheets to provide each of said work-sheets or packs of work-sheets with the correct number of carbon-sheets, said groups of carbon-sheets being one above the other, and 15 so positioned as to permit said work-sheets or packs of work-sheets to be kept permanently interleaved with said carbon-sheets, and so that one of said work-sheets or packs of work-sheets may be fed through said machine and be typed upon without removing 20 entirely the others of said work-sheets or packs of work-sheets from said machine.

7. In a typewriting machine, in combination, a platen, feed-rolls to guide a plurality of superposed packs of work-sheets successively or alternately underneath and around said platen, and a carbon-carrier comprising a base to which are fastened a plurality of plates one above another and bearing carbon-holding blades to which are secured carbon-sheets, each of said plates containing a sufficient number of carbon-holding blades to provide each of said plurality of superposed packs of work-sheets with the correct 30 number of carbon-sheets, said plates with their carbon-holding blades being so positioned as to permit said work-sheets or packs of work-sheets to be kept permanently interleaved with said carbon-sheets, and so 35 that one of said work-sheets or packs of work-sheets may be fed through said machine and be typed upon without removing entirely the others of said work-sheets or packs of work-sheets from said machine.

45 8. In a typewriting machine, in combination, a platen, feed-rolls to guide a plurality of work-sheets or packs of work-sheets successively or alternately underneath and around said platen, and a carbon-carrier comprising a base to which are fastened a plurality of plates bearing carbon-holding blades to which are secured carbon-sheets, each of said plates containing a sufficient 50 number of carbon-holding blades to provide each of said plurality of work-sheets or packs of work-sheets with the correct number of carbon-sheets, said plates with their carbon-holding blades being so positioned as to permit said work-sheets or packs of work-sheets to be kept permanently interleaved with said carbon-sheets, and so 55 that one of said work-sheets or packs of work-sheets may be fed through said machine and be typed upon without removing entirely 60 the others of said work-sheets or packs of work-sheets from said machine.

work-sheets from said machine, each of said plates being provided near its forward edge with a paper-clamp to hold said work-sheets or packs of work-sheets, which are only partially inserted in said machine and 70 which are not being typed upon, in position while one of said work-sheets or packs of work-sheets is threaded through the machine.

9. In a typewriting machine, in combination, a platen, feed-rolls to feed work-sheets or packs of work-sheets, interleaved with carbons, successively or alternately underneath and around said platen, and a carbon-carrier to which said carbons may be fastened and on 80 which are mounted paper-clamps for the purpose of holding in inoperative positions all of said work-sheets or packs of work-sheets with the exception of the one which is being fed underneath and around said 85 platen to be typed upon.

10. In a typewriting machine into which fan-folded or superimposed work-sheet packs may be inserted, in combination with a platen and feed-rolls, a carbon-carrier movably mounted upon a work table or frame, and comprising a base having mounted thereon suitable plates superimposed over one another and separated by upright members, said plates each bearing a plurality of carbon-holding blades furnished with carbon-sheets and provided with paper-clamps for the purpose of holding some of said fan-folded or superimposed work-sheet 90 packs in inoperative positions after they have been interleaved with said carbon-sheets, and so they may be carried backwardly and forwardly with said carbon-carrier during the process of alternately feeding another one of said fan-folded or superimposed work-sheet packs underneath and around said platen to be typed upon and of withdrawing it to strip the carbons therefrom.

11. In a typewriting machine, in combination, a platen, feed-roll mechanism, a work-presenting frame at the rear of said platen, superimposed transverse members bearing paper-guides at the rear of said work-presenting frame over which work-sheet units may be drawn, a carbon-carrier mounted to be moved forwardly and backwardly upon said work-presenting frame, said carbon-carrier comprising a plurality of plates superimposed one over the other and separated by posts to permit a plurality of work-sheet units or packs to be drawn between and above said plates, there to be interleaved with carbon-sheets secured to carbon-holding blades mounted on said plates, and means to retain the folded back leading edges of some of said work-sheet units or packs while the leading edge of one of said work-sheet units or packs is inserted underneath and around said platen to be 110 115 120 125 130

11 typed upon, said folded back leading edges of some of said work-sheet units or packs being retained in this inoperative position during successive forward and backward 5 movements of said carbon-carrier when stripping said work-sheet unit or pack that is in operation of its carbon at the conclusion of each typing operation on that pack and when it is being fed forward during 10 each typing operation.

12. In a typewriting machine, a carbon-carrier adapted to be moved forwardly and backwardly upon a work-presenting frame, said carbon-carrier comprising a lower plate 15 mounted directly upon said frame, and a middle plate secured to said lower plate by a plurality of studs and key-levers, and supporting an upper plate by means of a plurality of posts provided with reduced upper 20 portions which fit into corresponding openings in said upper plate, said upper and middle plates each being provided with a plurality of carbon-holding blades between which may be inserted the work-sheets of 25 two fan-folded webs or sets of plies in such a manner as to interleave, between said work-sheets, carbon-sheets fastened to said carbon-holding blades, each of said upper and middle plates being further provided with 30 paper-clamping members so that the leading edge of one of the fan-folded webs or sets of plies may be folded back and held in an inoperative position by its respective paper-clamping member while the other of said 35 fan-folded webs or sets of plies may be carried forward and threaded underneath and around the platen of said machine to a position to be typed upon, the inoperative fan-folded web or set of plies being carried forwardly and backwardly with said carbon-carrier as the operative fan-folded web or set of plies is being alternately stripped of its 40 carbons or fed forward during the process of typing.

45 13. In a typewriting machine, a carbon-carrier adapted to be moved forwardly and backwardly upon a work-presenting frame, said carbon-carrier comprising a lower plate mounted directly upon said frame, and a middle plate secured to said lower plate by a plurality of studs and key-levers, and supporting an upper plate by means of a plurality of posts provided with reduced upper 50 portions which fit into corresponding openings in said upper plate, said upper and middle plates each being provided with a plurality of carbon-holding blades between which may be inserted the work-sheets of two fan-folded webs or sets of plies in such a 55 manner as to interleave, between said work-sheets, carbon-sheets fastened to said carbon-holding blades, each of said upper and middle plates being further provided with paper-clamping members so that the leading edge 60 of one of the fan-folded webs or sets of plies

may be folded back and held in an inoperative position by its respective paper-clamping member while the other of said fan-folded webs or sets of plies may be carried forward and threaded underneath and around the platen of said machine to a position to be typed upon, the inoperative fan-folded web or set of plies being carried forwardly and backwardly with said carbon-carrier as the operative fan-folded web or set of plies is being alternately stripped of its carbons or fed forward during the process of typing, and a plurality of transverse web or ply supporting rods, fitted with paper-guides, mounted on the rear of said work-presenting frame to keep the trailing ends of said fan-folded webs or sets of plies separate from one another and support them as they are being fed through said carbon-carrier. 70 75 80

14. In a typewriting machine, the combination with a line-spacing revoluble platen, of a carrier in rear thereof, two sets of carbon-carrying blades, for carrying carbons interleaved between plies of work-webs, and a mount for each set, one mount being supported above the other upon said carrier, the lower work-web passing through the lower set of blades and beneath the upper mount. 85 90

15. In a typewriting machine, the combination with a line-spacing revoluble platen, of a carrier in rear thereof, two sets of carbon-carrying blades, for carrying carbons interleaved between plies of work-webs, a mount for each set, one mount being supported above the other upon said carrier, the lower work-web passing through the lower set of blades and beneath the upper mount, said carrier being movable with the platen at the line-spacing operations, and separate guides in rear of said carrier, one above the other, for leading the respective work-webs into the machine. 95 100 105

16. The combination with a line-spacing revoluble platen, of two independent sets of carbon-carrying blades in rear of said platen, and means for guiding work-webs into the machine to said carbon-carriers, through which they are threaded preparatory to passing to the platen, each web with its carbon-carriers being usable while the other web with its carbon-carriers are out of use, the web threaded through one of said carbon-carriers being below the other set of carbon-carriers, and means being provided to stow in a position of disuse the leading portion of either web with its carbons, preparatory to bringing into use the other web with its carbons. 110 115 120

17. The combination with a line-spacing revoluble platen, of two independent sets of carbon-carrying blades in rear of said platen, means for guiding work-webs into the machine to said carbon-carriers, through which they are threaded preparatory to 125 130

passing to the platen, each web with its carbon-carriers being usable while the other web with its carbon-carriers are out of use, the web threaded through one of said carbon-carriers being below the other set of carbon-carriers, and means being provided to stow in a position of disuse the leading portion of either web with its carbons, preparatory to bringing into use the other web

with its carbons, and a reciprocable carrier 10 upon which both of said sets of carbon-blades are mounted for line-space movement with the platen.

GEORGE W. RENZ.
